CHARLES M. CALDWELL, OF CHAMPAIGN, ILLINOIS, ASSIGNOR TO H. W. CALDWELL,
OF CHAMPAIGN, ILLINOIS.

PUNCHING-MACHINE.

1,369,322.

Specification of Letters Patent. Patented Feb. 22, 1921.

Application filed October 10, 1919. Serial No. 329,668.

To all whom it may concern:

Be it known that I, CHARLES M. CALDWELL, a citizen of the United States, residing at Champaign, in the county of Champaign and State of Illinois, have invented certain new and useful Improvements in Punching-Machines; and I do hereby declare the following to be a full, clear, and exact description of the same, reference being had to the accompanying drawings, forming part of this specification.

This invention relates to punching machines and has for its object the provision of a machine for forming ears or lateral projections on connector pins or nails commonly used for securing sectional insulators in place, these ears being formed on the pin after the same has been placed through the sections of the insulator and at such a distance from the head of the pin as to permit a slight movement of the sections toward and away from one another.

In the accompanying drawings:

Figure 1 is a side elevation of the machine constituting the present invention;

Fig. 2 is a similar view showing the parts in operated position;

Fig. 3 is a detail view of the dies; and

Fig. 4 illustrates an insulator nail extending through the insulator and provided with ears or projections for retaining it therein.

As shown in Fig. 1, the machine embodies a frame formed of a base 1 and an upper portion 2 which is made integral with the base and overhangs the same. Seated in the base 1, and projecting upwardly therefrom a short distance is a die 3 and extending downwardly through a passage 4 in the overhanging portion 2 of the frame is a second die 5, positioned in vertical alinement with die 3. Normally the two dies are held with their adjacent ends spaced a short distance apart, the lower die 3 being fixed in the base 1 by a set screw 6 and the upper die 5 being maintained with its lower end spaced a short distance from the adjacent end of die 3 by means of a spring 7 interposed between the top face of the frame and a collar 8 formed on the upper end of said die. Die 5 is prevented from moving upwardly out of the frame by a set screw 9 engaging shoulder 10 formed by the end of a groove 11 in said die into which said screw 9 extends. This screw, working in

this groove, also performs another function 55 which will appear hereinafter.

Preferably the dies 3 and 5 are circular in cross section and to render them durable they are of a relatively large diameter but as it is desired to form relatively small ears 60 or fins on the insulator nails, said dies are tapered on their opposite sides at their adjacent ends, thus forming a narrow, elongated plane face 12 on said ends. Each of these end faces 12 is provided, preferably 65 at its center, with a recess 13 to form a pair of shoulders 14 on each die, the distance between the shoulders of the respective dies being less than the width of the insulator nail or other article to be operated upon. 70

Lower die 3 being fixed in the base 1, groove 11 is so located in the upper die 5 that when said die is secured in position by screw 9, the end faces 12 of the dies will extend parallel to each other and the shoulders 14 on said faces will be vertically opposed to each other, these relative positions being permanently maintained by the screw and groove.

In operation the insulator nail is first 80 placed through the insulator sections and its protruding, unheaded end positions horizontally on die 3 between shoulders 14, with the greater portion of its body lying above the face of die 3, due to the fact that 85 the distance between the shoulders 14 is less than the width of the pin. A blow is then delivered with a hammer, or other tool, upon the head formed by shoulder 8 on die 5, driving this down on die 3, whereupon 90 a small portion of the body of the nail will be extruded by the shoulders 14, the greater portion of the nail body being received in the recesses 13. These extruded portions form the ears or fins 15, as illustrated in 95 Fig. 4, and preferably they are spaced a sufficient distance from the head of the nail to permit the insulator sections to be moved apart.

What is claimed is:

1. In a machine of the character described, the combination of a stationary and a movable die positioned in alinement with each other, the adjacent ends of the dies being elongated and relatively thin, a pair of 105 integral shoulders on each of the adjacent thin ends of the dies, there being a recess in the face of each die between said shoulders,

- the distance between the shoulders on the respective dies being less than the width of the article operated upon, whereby when the dies are moved toward each other a small portion of the body of the article will be extruded and formed into relatively narrow fins on each side of the article and the major portion of the body of the article will be received in said recesses.
- 10 2. In a machine of the character described, the combination of a stationary die and a movable coöperating die of comparatively large cross section throughout the greater portion of their length, the adjacent 15 end portions of the dies being tapered to

form elongated and relatively thin end faces, a pair of thin shoulders on each of the adjacent end faces of the dies, the shoulders on the respective dies being spaced apart a distance less than the width of the 20 article operated upon, whereby when the dies are moved toward each other a small portion of the body of the article will be extruded and formed into a relatively narrow fin on each side of the article and the 25 major portion of the body will be received in the space between the shoulders on the dies.

CHARLES M. CALDWELL.
